UNITED STATES PATENT OFFICE.

WILLIAM H. McFALL, OF PHILADELPHIA, PENNSYLVANIA.

PENCIL-SHARPENER.

SPECIFICATION forming part of Letters Patent No. 760,749, dated May 24, 1904.

Application filed September 22, 1903. Serial No. 174,141. (No model.)

To all whom it may concern:

Be it known that I, WILLIAM H. McFALL, a citizen of the United States, residing at Philadelphia, county of Philadelphia, and State of Pennsylvania, have invented a certain new and useful Improvement in Pencil-Sharpener, of which the following is a specification.

My invention relates to a new and useful improvement in pencil-sharpener, and has for its object to provide a pencil-sharpener which may be made at a comparatively small price and yet will provide a sharpener which is exceedingly durable and efficient and which will sharpen a pencil quickly and without soiling the hands.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a perspective view of my improved sharpener in use; Fig. 2, a plan view of the same; Fig. 3, a section on the line 3 3 of Fig. 2.

The sharpener consists of a flat plate of steel stamped out in the form of an elliptical ring A, the inner edge at each end being beveled, and sharpened, so as to form cutting edges, as shown at B. The ring is corrugated across its shortest diameter, as illustrated at C, so as to form a lateral groove D upon each side. The concaved surfaces of these corrugations are roughened similar to a file, so that the lead of the pencil may be pointed by rubbing it in these grooves. The sharpener is designed to be used as shown in Fig. 1. It is held between the thumb and first or index finger and supported by the second finger. The pencil is held down on a table or desk and turned with one hand and drawing the sharpener gently over the pencil with the other hand, cutting as you would with a penknife.

With this sharpener any shape point desired

can be made, and the corrugations afford a firm grip of the sharpener and also serve to hold the sharpener from lying flat upon a flat surface, so that it may be picked up easily at any time, and the corrugations also prevent, to a certain extent, the edges coming in contact with other objects which would damage the same.

Of course I do not wish to be limited to the exact construction here shown, as slight modifications could be made without departing from the spirit of my invention.

Having thus fully described my invention, what I claim as new and useful is—

1. A pencil-sharpener formed of a flat elliptical ring, the inside edges of the ring at each end of its longest diameter sharpened so as to form cutting edges, and roughened or filed surfaces formed upon each side of the ring, as and for the purpose specified.

2. A pencil-sharpener consisting of a flat metallic ring, the inside edges of the ring at each end sharpened so as to form cutting edges, enlargements formed upon the ring at each side of its shortest diameter, roughened or flat surfaces formed upon each face of the ring, as and for the purpose specified.

3. A pencil-sharpener consisting of a flat elliptical metallic ring, the inside edges at each end of its longest diameter sharpened to form cutting edges, corrugations formed in the end across its narrowest diameter, as and for the purpose specified.

4. A pencil-sharpener consisting of a flat elliptical metallic ring, the inside edges at each end of the ring sharpened so as to form cutting edges, corrugations formed in the ring across its narrowest diameter, the concaved surfaces of said corrugations being roughened, as and for the purpose specified.

In testimony whereof I have hereunto affixed my signature in the presence of two subscribing witnesses.

WILLIAM H. McFALL.
